(57) **CLAIM**

The ornamental design for a cookware vessel lid and handle set, as shown and described.

DESCRIPTION

FIG. 1 is a perspective view of the cookware handle of the cookware vessel lid and handle set, showing my new design; FIG. 2 is a right side elevation view thereof; the left side elevation view being the mirror image thereof; FIG. 3 is a top plan view thereof;

FIG. 4 is a bottom plan view thereof;

FIG. 5 is a front elevation view thereof;

FIG. 6 is a back elevation view thereof;

FIG. 7 is a perspective view of the cookware lid handle of the cookware vessel lid and handle set, showing my new design;

FIG. 8 is a right side elevation view thereof; the left side elevation view being the mirror image thereof;

FIG. 9 is a top plan view thereof;

FIG. 10 is a bottom plan view thereof;

FIG. 11 is a front elevation view thereof;

FIG. 12 is a back elevation view thereof;

FIG. 13 is a perspective view of the cookware vessel lid and handle set, showing my new design;

FIG. 14 is a right side elevation view thereof;

FIG. 15 is a top plan view thereof; and,

FIG. 16 is a cross-sectional view thereof taken at section line 16-16 in FIG. 15.

The broken lines in FIGS. 13-16 showing a cookware vessel illustrate environment and form no part of the of the claimed design. All other broken lines in the drawing views represent portion of the cookware vessel lid and handle set and form no part of the claimed design.
